UNITED STATES PATENT OFFICE.

ALEXANDER P. WADDELL, OF UNION CITY, TENNESSEE.

BUCKLE.

SPECIFICATION forming part of Letters Patent No. 377,656, dated February 7, 1888.

Application filed June 28, 1887. Serial No. 242,801. (No model.)

To all whom it may concern:

Be it known that I, ALEXANDER P. WADDELL, of Union City, in the county of Obion and State of Tennessee, have invented a new and useful Improvement in Buckles, of which the following is a specification.

My invention relates to a buckle designed especially for use as a trace-carrier to be attached to the back-strap of harness, wherein 10 a flexible strap, preferably of heavy drilling, is passed over the animal's back and through the buckle in such manner that the hook and staple on the buckle, which form the eye for the trace-link, are securely closed and held together by the tension of the band upon the buckle, and which reduce the pull on the spurs of the buckle by passing the band over friction-bars, so as to prevent wear of the band, as will hereinafter appear.

20 In the accompanying drawings, Figure 1 is a side elevation showing the preferred form of construction; Fig. 2, a section in line $\alpha\alpha$ of Fig. 1. Fig. 3 is a face view of a buckle constructed according to my invention, and 25 embodying a modification of the hinge-connection of the plates; and Fig. 4 is a sectional elevation of the construction shown in Fig. 3.

The buckle A is composed of two plates, 1 and 2, hinged together at 3. The plate 1 has 30 a keeper, 4, which passes through an opening, 5, in the plate 2, and the plate 2 has a hook, 6, which when closed engages with the keeper 4 and holds the link of the trace upon the buckle. The plate 1 of the buckle, as shown 35 in Figs. 1 and 2, has cross-bars 7 and 8 at its upper end and a slot, 9, at its lower end, around and through which slot the belly-strap C of the harness is passed to secure the buckle thereto, and the plate 2 has spurs 10, which 40 pass through the back-strap B, and serve both to hold the plates 1 and 2 together and to close the hook 6 securely upon the keeper 4, and thus lock the link of the trace upon the buckle. The upper end of the plate 1 is 45 rounded at 11 to secure a good bearing over which the strap A may be drawn, and the bars 7 and 8 are egg-shaped in cross-section, the ends of largest diameter being arranged as shown in Fig. 2, to present a greater bearing- 50 surface to the strap and economize space.

The sections or plates 1 and 2 are perforated at 12 to lighten and ventilate the sections, and

the section 1 has pads 13 secured to it by stitches passing through the said perforations 12, which prevent the buckle from chafing or 55 injuring the animal by rubbing against it. The keeper 4 is recessed at 14 to receive a jaw, 15, upon the hook 6 and interlock the said hook with the keeper and effectively prevent the displacement of the trace-link from 6c the hook, unless the plate 2 is swung out a considerable distance from the plate 1.

In the modification shown in Fig. 3 the plate 1 has ears 16, to which the bars 7 and 8 are permanently secured, and which have hinge- 65 projections 17 entering openings 18 in lugs or ears upon the upper corners of plate 2. In both forms of construction hereinbefore described the strap B passes under the bar 7, over the bar 8, and around the rounded portion 11 of the plate 1. From thence the strap passes under said plate to the lower edge thereof, and then through the slot 9, and, being pierced by the spurs 10 of the plate 2, is held securely upon the buckle. The buckle may 70 be adjusted upon the strap by first drawing the strap down until it is sufficiently slack to be disengaged from the spurs 10, and the buckle then moved thereon to the position required.

80 The construction shown in Figs. 3 and 4 comprises a plate, 1, having a keeper, 4, and a slot, 19, and ears 16 at its upper end and a slot, 9, at its lower end. The plate 2 has a hook, 6, which engages with the keeper 4 of 85 plate 1, spurs 10 upon the lower edge thereof, and ears 21 at the upper end thereof. A bar, 22, passes through the ears 16 and 21 of plates 1 and 2, and serves not only to secure them together, but provides a bar around which the 90 strap B may be passed to provide a friction-bearing similar to that employed in the devices shown in Figs. 1 and 2. In the construction shown in Fig. 4, last described, the strap passes up through slot 19, around the 95 bar 22, thence down through the slot 19, and under the plate 2 to the slot 9, and up through said slot. The spurs 10 are then passed through the strap to secure the buckle upon it and hold the hinged plate closely folded upon the 100 sliding plate of said buckle.

I claim as my invention and desire to secure by Letters Patent—

1. In a trace-carrier buckle, the combina-

tion, with the sliding plate having means for attachment to the strap, of the hinged plate permanently secured to and adapted to fold thereon, said plates being provided each with 5 a part, which parts interlock and serve to receive and hold the trace, substantially as described.

2. In a trace-carrier buckle, the combination, with the sliding plate 1, having cross-bars and slots to receive the strap, and an outwardly-projecting keeper, of the plate 2, hinged to the plate 1, having a hook to receive the trace-link, and an opening, 5, in the same, through which the keeper of the plate 1 may 15 project, substantially as described.

3. In a trace-carrier buckle, the combination, with the sliding plate 1, having cross-bars and slots to receive the strap, of a hinged plate, 2, having a hook to receive the trace-link, and spurs upon its swinging edge, which 20 project across the slot 9 and pass through the said strap, substantially as described.

4. In a trace-carrier buckle, the combination, with the sliding plate 1, having cross-bars 7 and 8, of egg-shaped cross-section, arranged as herein described, of a rounded plate,

11, and a slot, 9, over and through which the strap to which the buckle is secured may be passed, substantially as described.

5. In a trace-carrier buckle, the combination, with the sliding plate 1, of the recessed keeper 4 and the plate 2, hinged to said sliding plate, having an opening, 5, through which said keeper may pass, and a hook, 6, formed to support the trace-link and interlock with 35 the recess in the keeper, substantially as described.

6. A plate, 2, having a hook, 6, formed to support a trace, and an opening, 5, combined with a plate, 1, pivotally connected with plate 40 2, and having a keeper, 4, which projects through opening 5 and adjacent to the hook 6, whereby to retain the trace in engagement therewith, substantially as set forth.

7. In a trace-carrier buckle, the perforated 45 sliding plate 1, and the hinged plate 2, and a pad, 13, secured to the perforations of plate 1, substantially as described.

ALEXANDER P. WADDELL.
